Attorney,

UNITED STATES PATENT OFFICE.

WILLARD G. BRATTON, OF PITTSBURGH, PENNSYLVANIA.

DESIGN FOR A WIND-SHIELD FOR MOTOR-VEHICLES AND THE LIKE.

45,327.

Specification for Design.

Patented Mar. 3, 1914.

Application filed November 29, 1913. Serial No. 803,851. Term of patent 7 years.

To all whom it may concern:

Be it known that I, WILLARD G. BRATTON, a citizen of the United States, residing at Pittsburgh, in the county of Allegheny and State of Pennsylvania, have invented a new, original, and ornamental Design for Wind-Shields for Motor - Vehicles and the like, of which the following is a specification, reference being had to the accompanying drawing, forming part thereof.

Figure 1 is a front elevation, and Fig. 2 is a side elevation, of a wind shield, showing my new design.

I claim:

The ornamental design for a wind shield for motor vehicles and the like, as shown.

WILLARD G. BRATTON.

Witnesses:

ELBERT L. HYDE,
WILLIAM B. WHARTON.
